S. K. SMITH,
FOUNDATION APPARATUS,
APPLICATION FILED DEC. 2, 1910.

987,266.

Patented Mar. 21, 1911.

UNITED STATES PATENT OFFICE.

STEWART K. SMITH, OF VINTONDALE, PENNSYLVANIA.

FOUNDATION APPARATUS.

987,266.

Specification of Letters Patent. Patented Mar. 21, 1911.

Application filed December 2, 1910. Serial No. 595,177.

To all whom it may concern:

Be it known that I, STEWART K. SMITH, a citizen of the United States, residing at Vintondale, in the county of Cambria and State of Pennsylvania, have invented certain new and useful Improvements in Foundation Apparatus; and I do hereby declare the following to be a full, clear, and exact description of the invention, such as will enable others skilled in the art to which it appertains to make and use the same.

My invention consists of apparatus for excavating and preparing foundations, and is particularly applicable to those which are sunk in soft soil, sand, gravel or the like, and is also especially adapted for such work which extends under water.

My apparatus is mounted on a platform which can be used either on dry land, or over water, or where the foundations are to be prepared under a body of water, I may use a scow, barge, or other floating support.

In case I desire to use my apparatus on land which has either a level or an irregular surface, I construct a platform or support for the same, of timber, the details of which are immaterial, the principal requisite of same being that it shall be of size and strength for holding my apparatus thereon, and if desired, to be capable of being moved from place to place. This lower support or platform may be similar in plan to that shown on the drawing herewith, but the platform itself need not be as thick as the scow which is illustrated, and said platform may be supported on columns, trestles, blocking, or other constructions. I have not illustrated a platform in the drawing herewith, as the above description is deemed sufficient to enable any mechanic to construct the same.

The drawings accompanying this specification show, for convenience of illustration, a scow for supporting the mechanical portions of my apparatus, and this may also carry the concrete shell or lining or other materials.

My apparatus comprises a metal pipe, or hollow shaft, open at the bottom and carrying an expanding cutting tool near its lower end; this pipe is connected at its top through a coupling having a suitable stuffing box

which allows the pipe to revolve while the coupling is held in place and connected by a pipe or flexible hose to a pump, siphon or other suction and lifting apparatus. This pipe, with its attachments is supported from a platform or frame, mounted on the scow, by means of an adjustable suspension rod, and is thereby adapted to be raised and lowered as desired.

A tube or trough is adapted to discharge water into the excavation, if desired, said discharge pipe being connected with a centrifugal pump, or other source of water supply under such pressure as may be required.

The pipe or hollow shaft heretofore mentioned is provided with means for revolving the same and the expanding cutting tool carried thereby, and means are also provided for expanding or contracting said cutting tool, if desired.

As the cutting tool is revolved and lowered within the excavation, I support the sides of said excavation by a hollow cylindrical shell of concrete or other material surrounding said pipe at a suitable distance therefrom, the said shell being composed of sections of suitable size which are put in from time to time, as required, by the lowering of the previous ones. This cylindrical shell is supported by a series of rods or other means, which are in turn carried by a trestle or framework mounted on the scow, and said trestle or framework may be adapted to be moved up and down bodily, and the rods supporting the shell are also capable of separate up and down movement and adjustment for a similar purpose. As the expanding cutting tool is lowered and revolved, water is supplied to the excavation, if desired, by the tube or trough heretofore mentioned, and this water, carrying with it the excavated material, is withdrawn from the excavation by the pump or suction apparatus. If water naturally collects in the excavation, no extraneous supply of water is needed. As the expanding cutting tool is lowered it is maintained at an approximately uniform diameter to correspond with that of the exterior of the shell or lining, and after it has reached the required depth, it may be expanded and the revolution and excavation continued, whereby a spread footing or base is provided for the

excavation. After the excavation is completed as just described, the cutting tool is contracted, and lifted out of the excavation by raising the pipe or hollow shaft, on the 5 lower end of which said cutting tool is mounted, the rods for supporting the shell etc., are then withdrawn, and the interior filled with concrete or other material, thus providing a substantial foundation with an 10 enlarged footing. By this means I provide a foundation, the major portion or shaft of which is of comparatively small size, thus 15 conducting to economy of excavation and foundation material, while the footing for same is enlarged, thereby giving it a much 20 greater capacity for supporting loads, or other purposes, as desired. This spread footing is particularly useful in making foundations in soft material, as I can therefore 25 by reduce the depth and size of the foundation in general, on account of the enlarged footing and consequent increased bearing capacity of same; but in other cases I may continue the excavation until a hard stratum is reached; in which instances the spread 30 footing may not be needed.

Having thus given a general description of my invention, I will now, in order to make the same more clear, refer to the annexed sheet of drawings in which like 35 characters of reference represent like parts.

Figure 1 is a diagrammatic cross sectional elevation of my apparatus in place, mounted on a scow adapted to float in water and 40 to be anchored at the chosen location therein. Fig. 2 is a diagrammatic plan view of my apparatus. Fig. 3 is a central, vertical sectional elevation of my expanding cutting tool, mounted on the pipe within the excavation; the cutting tool in this view being expanded to the extent necessary for preparing the bore for the cylindrical shell. Fig. 4 is a vertical central cross section on a reduced scale of one of my complete 45 foundation piers or piles with a spread bottom. Fig. 5 is a detail drawing on a larger scale than Fig. 1 showing the gears 10 and 11 and the construction for maintaining them in mesh with each other, and also 50 shows a spline by which the gear 10 revolves the hollow shaft 9. Fig. 6 is a cross sectional elevation of the lower part of my casing showing the dowel or tongue and groove sections and method of supporting 55 and lowering same by means of the hooks on the rods 19 and also shows bands or wires securing together the two halves or portions of each section of the casing forming one ring.

60 Referring now to the various characters of reference on the drawings:—1 indicates the scow or platform on which my apparatus is mounted, provided with spuds or anchors 2 which are adapted to be raised

and lowered and secured in position by 65 means of rack and pinion, block and tackle, or other suitable means, not shown. After the scow or platform is located in position for operation, the spuds are forcibly projected downward on, or into the bottom, and 70 then secured, and after the operation of preparing one foundation is completed, the anchors are withdrawn and the operation repeated elsewhere.

On the scow are the supports 3 shown as 75 hydraulic or fluid pressure cylinders provided with inlet and outlet openings 4 for the reception of fluid under pressure and discharge of the same therethrough, thereby raising or lowering the plungers 5 and 80 the attached cross pieces 6 as desired. The fluid pressure may be provided from any suitable source and controlled by valves, not shown. Although I have shown these supports 3 as fluid pressure cylinders, the 85 platform, cross pieces and attachments may be supported and adjusted in any other manner, as may be expedient or desirable.

Although for convenience of illustration I have shown the beams 6 at a comparatively low elevation and the supports 5 as rather short and of small movement, I may, of course, place these beams higher and make the supports longer and of greater movement, if necessary, to properly handle 95 the parts attached thereto.

On the cross pieces 6 is mounted the beam 7 through which passes the rod 8, provided with a collar and set screw, or other adjusting means, to form a variable support for 100 the pipe or hollow shaft 9 on which the bevel gear 10 is secured, but slidably mounted in a longitudinal direction, for the purpose of revolving said pipe or shaft and the cutting tool attached to the lower end thereof. 105 The bevel gear 10 is revolved by the bevel pinion 11 which is connected with any suitable source of power. As shown in Fig. 5 the bevel gear 10 is supported by the duplex bearing 40 which has a bearing which also 110 maintains the bevel pinion 11 in mesh with the bevel gear 10, while at the same time the bevel gear 10 is slidably mounted on the hollow shaft 9 and is adapted to revolve 115 said shaft by means of the spline or feather 41.

Referring to Fig. 6:—rods 19 are shown as made in sections which are coupled together by means of internally threaded screw sockets 42 which fit on the corresponding external threads on the rod sections after the fashion of a pipe joint, and the rod 8 may be similarly joined together in sections, if desired, or all these rods may be joined together in sections with joints flush 120 on the outside, all as elsewhere referred to herein.

At the upper end of the pipe or hollow

shaft 9 is a coupling and stuffing box 12 which is constructed after the fashion of a swivel so as to permit revolution of the pipe 4, while maintaining a tight connection of the hose or flexible pipe 13 with the interior thereof. The flexible hose 13 is connected to the centrifugal suction pump 14, or to a siphon or other means for drawing excavated materials mixed with water, from the bottom of the excavation through the hollow shaft 9 and discharging the same where desired.

The tube or hose 15 is adapted to discharge water into the excavation, if desired, and is connected with a centrifugal pump indicated as 16, or to other means for this purpose, the suction pipe of said pump being indicated as 17.

The cylindrical casings of the excavation are indicated as 18 and may be composed of concrete or other material made in sections, as shown, and for convenience of placing in position, these are each preferably formed as halves or portions of a cylindrical annulus and provided with tongues and grooves, dowels, or other means for holding them in position with relation to each other.

As shown in Fig. 6 the casing or hollow shell is composed of the sections 18, the various rings of which are preferably made in halves as indicated by the longitudinal joint 36 and the adjoining rings are maintained in relation with each other by means of the dowels or tongues and grooves 33. If desired, the aforesaid portions of each ring of said shell or casing 18 may be secured together by means of a flat band indicated by 34, or by means of a wire twisted around same indicated as 35.

37 indicates a hook formed on the lower end of one of the rods 19 adapted to fit into the hole 38 in the lower ring or casing 18 for the purpose of supporting and lowering same in position, and said hook may be discharged therefrom by lowering the rod 19 and pulling it sidewise, as will be evident.

39 indicates the hook on the lower end of one of the rods 19 adapted to engage the lower edge of the bottom sections of the cylindrical casing 18 for the purpose of supporting and lowering same, the disengagement of this hook being accomplished when desired, by lowering the same after the casing is otherwise supported, either by friction or by contact with the lower portion of the excavation. The hook may then be pushed to one side or turned around and partially revolved or withdrawn. This casing composed of sections 18 is supported and lowered by means of the rods 19, the lower ends of which engage the lower shell 18 by hooks 37 or 39, while the upper ends of said rods pass through the beams 20 and are ad-

justably supported on same by means of 65 slideable collars and set screws as indicated, or by other means as desired. In order to allow for greater or less depth of excavation and to permit easy handling of the rods 19, these may be made in sections or shorter 70 lengths screwed together as required, and this is similarly true of the rod 8 which supports the pipe or hollow shaft 9 and its attachments. The rods 19 which support the shell or casing, and the rod 8 which supports the 75 pipe or hollow shaft 9 and its attachments, may each be made in one long length, or may be made in sections screwed or jointed together after the fashion of a pipe coupling with threaded ends and coupling sockets, or 80 they may be jointed by having successive sections, one with male and the other with female thread. As this latter joining of rods is a well known and customary construction, it is not illustrated, as it will be 85 obvious to any mechanic.

Referring now to my expanding cutting tool as particularly shown in Fig. 3, this is mounted on the lower end of the pipe or hollow shaft 9 which is provided with a spline or feather 22. The expanding cutting tool is made in the form of a toggle and has cutting members 21 pivoted near the bottom of the pipe by the pins 23 which in turn are secured through the extensions or lugs of the lower collar 24, which collar is firmly secured at the lower end of the shaft 9 by rivets or bolts as shown, or by other means. The upper members of my expanding cutting tool are indicated as 25 and are pivoted at their lower ends to the upper ends of the cutting members 21 as shown, the upper ends of said members 25 being pivotally secured to the sliding collar 26 mounted on the shaft 9 as shown, and prevented from 105 turning thereon by the spline or feather 22 and a corresponding groove in the collar 26. The collar 26 and thereby the upper ends of the members 25 are connected with the adjusting rod 27 which is capable of movement 110 up or down as desired, for the purpose of expanding or contracting said cutting tool, and holding it at the required amount of opening as desired. The adjusting rod 27 extends above the platform of my apparatus 115 to a convenient location and is there provided with adjusting and clamping means indicated as the collar and set screw 28 and the guiding collar 31 secured to the pipe 9. By moving this rod 27 downward, the tool is expanded, and by moving the same in a reverse direction, the tool is contracted, and by holding same in position by means of the clamping arrangement 28 it is held in any required position to produce a hole of the 125 diameter desired.

One of my completed foundations as shown in Fig. 4 is composed of an inclosing

cylindrical shell 18, the filling of concrete, masonry, or other material within the same, being indicated as 29 and the spread footing of similar material indicated as 30.

5 The scow 1 is provided with a central opening 32, said scow surrounding three sides of said opening to allow easy access to the locality of the operations, while permitting the scow to be withdrawn thence, or 10 replaced as desired, without interfering with the finished or partially finished work.

The expanding cutting tool as shown by full lines in Figs. 1 and 3 is adjusted for excavating a cylindrical hole of diameter to 15 accommodate the shell 18, while the dotted lines at the lower part of Fig. 1 show an excavation of greater diameter with the cutter more expanded, for the purpose of providing an enlarged footing.

20 Where the foundations are made under water and in soil such that water would collect within the foundation, it will be unnecessary to supply same by means of the tube 15, as in such cases, the water which naturally flows into the opening will suffice for loosening the earthy materials and aid in carrying them out by means of the suction apparatus.

Although I have shown the suction apparatus as mounted on the scow or platform, I may place a siphon, ejector or other suction and pumping apparatus within the casing at a lower level in order to make a deeper foundation than suction alone will 35 permit.

Having thus described my improved apparatus, I will now explain its operation in connection with a scow which is adapted to float on the surface of the water, although 40 my apparatus may be mounted upon a platform or trestle on land or water, as desired.

The scow 1 containing my apparatus is floated over the point where it is proposed to sink the foundation, and is secured in position by means of the spuds or anchors 2, one or more lower sections of the cylindrical shell 18 are placed over the opening 32 in the scow and supported and adjusted therein by the suspending rods 19. These bottom 45 sections are then lowered by means of said rods, or the entire platform 6 may be lowered by means of the fluid pressure cylinders 3, and the plungers 5, until the bottom sections of the shell rest upon the surface of 50 the ground. This is continued until sufficient sections of the shell are in preliminary position, whereupon the cutting tool, mounted on the pipe or hollow shaft 9, is lowered inside the shell until it reaches the earth. 55 I can, however, first place the cutting tool in 60 position on the surface of the ground and then place the shell sections around it, as required. The shell sections, may, if necessary, be surrounded by metal bands, wires,

or other binders, to more firmly secure them 65 in position. The sections of the shell or hollow casing made in halves, may be secured together by means of metal bands 34 or wire 35, as shown in Fig. 6. The lower shell sections and the cutting tool now being 70 in position, with their lower ends resting on the ground, the upper end of the pipe 9 is connected by means of the flexible hose 13, with the centrifugal pump or other suction apparatus 14, and water is then discharged, 75 if required, through the tube 15 into the interior of said shell. The expanding cutting tool is then revolved by means of the shaft 9 and its connections and as it turns the earth is loosened and washed up by the in-flowing 80 stream of water and carried away through the hollow pipe 9 and its connections 13. As the cutting tool is lowered it is partially expanded by means of the adjusting rod 27 until the diameter of the cut is as shown in 85 Figs. 1 and 3 being of size sufficient to allow the shell 18 to descend therein. This operation is continued as the cutting tool 21 excavates earthy materials, while the said mixture of water, earth, gravel, etc., is withdrawn through the hollow pipe 9, its connection hose or pipe 13 and the suction apparatus connected therewith. The cutting tool 90 as it is now revolving is lowered continuously as fast as it cuts, and additional sections 95 of the cylindrical casing 18 are put on as required by the descent of the previous section. This operation is continued until the required depth is reached, and, if desired, the cutting tool may then be expanded as indicated by the dotted lines in Fig. 1, thereby 100 providing an enlarged footing. This being accomplished, the cutting tool is contracted or folded up by means of the rod 27 and its attachments, and is then withdrawn from 105 the excavation. The opening of the excavation is then filled with concrete, masonry or other material, as desired, thereby providing 110 a solid foundation.

It is, of course, understood that I may 110 continue the excavation of a diameter about equal to, or slightly greater than, the external diameter of the shell 18, until hard material, is reached, or, in case of excessive depth of soft material, or for other reasons, 115 I may expand the cutting tool at the bottom thereof to provide an enlarged footing as shown, the amount of this expansion being to any extent within the capacity of 120 the tool, as desired.

Although I have shown and described my apparatus in some detail, I do not wish to be limited to the exact and specific details shown and described, but may use such substitutions, modifications or equivalents thereof, as are embraced within the scope of my invention, or as pointed out in the claims.

Having thus described my invention, what

- I claim and desire to secure by Letters Patent is:—
1. In apparatus of the character described, an expandible cutting tool adjustably mounted on a hollow shaft, means for revolving the same, and suction or pumping devices connected with said hollow shaft for receiving the excavated material therethrough. 65
  10. 2. A hollow casing made in sections, means for holding and lowering the same, a hollow shaft provided with an expandible cutting tool adapted to operate within said casing, means for revolving said shaft, and 70 suction or pumping devices connected with the same for removing the excavated material therethrough. 75
  20. 3. In apparatus of the character described, an expandible cutting tool of toggle construction, adjustably mounted on a hollow shaft, means for raising, lowering and revolving said shaft and the cutting tool carried thereby, a flexible hose or tube connected with said shaft and provided with 80 suction or pumping appliances whereby the excavated material may be discharged therethrough. 85
  30. 4. In apparatus of the character described, an expandible cutting tool adjustably mounted on a hollow shaft, means for raising, lowering and revolving the same, means for supplying water to the excavation made thereby, and suction or pumping devices connected with said hollow shaft for removing the excavated material therethrough. 90
  40. 5. In apparatus of the character described, an expandible cutting tool adjustably mounted on a hollow shaft, means for revolving the same, a rod connected with said hollow shaft and provided with means for raising, lowering and holding same, and suction or pumping devices connected with said hollow shaft for removing the excavated material therethrough. 95
  50. 6. In apparatus of the character described, an expandible cutting tool adjustably mounted on a hollow shaft, means for raising, lowering and revolving the same and the cutting tool carried thereby, a swiveling coupling mounted at the upper end and connected with the interior of said shaft, and with a flexible hose or tube provided with suction or pumping apparatus, whereby the excavated material may be discharged there- 100
  55. through. 105
  60. 7. An expandible cutting tool comprising a hollow revoluble shaft, a pair of cutting bars pivotally connected to the lower end thereof, a pair of upper members or links pivotally connected at the upper ends of said bars, the other ends of said links being pivoted on a sliding sleeve mounted on said shaft, said sleeve being prevented from turning by a groove therein and a corresponding feather on said shaft, an adjusting rod connected with said sliding sleeve and extending externally along said shaft, said rod being provided with adjusting and clamping means mounted near the upper end of said shaft, whereby the cutting tool may be expanded, contracted, or held as desired. 110
  115. 8. In apparatus of the character described, an expandible cutting tool mounted on a hollow shaft, said tool and shaft being adjustably supported from an overhead platform comprising hydraulic cylinders and plungers with cross beams mounted thereon, whereby said cutting tool and appurtenances may be raised, lowered or held in position as desired. 120
  125. 9. An expandible cutting tool comprising a hollow revoluble shaft, a pair of cutting bars pivotally connected at the lower end thereof, a pair of upper members or links pivotally connected to the upper ends of said bars, the other ends of said links being pivoted on a slidble sleeve mounted on said

shaft, said sleeve being prevented from turning by a groove therein and a corresponding feather on said shaft, an adjusting rod connected with said slideable sleeve and extending externally along said shaft, said rod being provided with adjusting and clamping means mounted near the upper end on said shaft, a flexible hose or tube connected with the interior of said shaft and provided with suction or pumping apparatus whereby the excavated material may be discharged therethrough.

14. An expandable cutting tool comprising a hollow revoluble shaft, a pair of cutting bars pivotally connected at the lower end thereof, a pair of upper members or links pivotally connected to the upper ends of said bars, the other ends of said links being pivoted on a slideable sleeve mounted on said shaft, said sleeve being prevented from turning by a groove therein and a corresponding feather on said shaft, an adjusting rod connected with said slideable sleeve and extending externally along said shaft, said rod being provided with adjusting and clamping means mounted on and near the upper end of said shaft, means for supplying water around said cutting tool, and a flexible hose or tube connected with the upper end of the interior of said shaft and provided with suction or pumping apparatus whereby the excavated material may be discharged therethrough.

15. A foundation apparatus comprising a movable scow or platform provided with means for securing same in position, an adjustable platform mounted thereon, to which is adjustably secured a hollow pipe or shaft carrying at its lower end an expandable cutting tool, means for expanding and contracting said tool, and for lowering, raising and revolving the hollow shaft aforesaid, and a flexible hose or tube connected with the interior of said shaft and provided with suction or pumping apparatus whereby the excavated material may be discharged therethrough.

16. In apparatus of the character described, an expandable cutting tool of toggle construction adjustably mounted at the lower end of a hollow shaft, means for revolving said shaft, an adjustable platform carried by a scow or trestle adapted to support said shaft, said platform being carried by hydraulic cylinders and plungers provided with means for holding, raising and lowering the same, whereby the cutting tool may be operated as desired, the upper end of said hollow shaft being provided with a flexible hose or tube connected therewith and provided with suction or pumping apparatus, whereby the excavated material may be discharged therethrough.

17. An apparatus of the character de-

scribed comprising a platform or scow surrounding three sides of an opening therethrough, within which is mounted a hollow shaft having an expandable cutting tool at the lower end thereof, means for raising, lowering and revolving said shaft and for adjusting the expandable cutting tool carried thereby, and suction or pumping devices connected with said hollow shaft for removing the excavated material therethrough.

18. An apparatus of the character described comprising a platform or scow having an opening or notch on one side thereof, said opening being free from obstructions at its outer edges, an expandable cutting tool of toggle construction adjustably mounted within said opening to operate therethrough, said cutting tool being carried on the lower end of a hollow shaft provided with means for raising, lowering and revolving same, and a tube or flexible hose connected with said shaft provided with suction or pumping devices whereby the excavated material may be discharged therethrough.

19. An apparatus of the character described comprising a platform or scow of approximately U-shaped form in plan, an expandable cutting tool adjustably mounted on a hollow shaft adapted to operate within the opening of said scow, means for raising, lowering and revolving said shaft and the cutting tool carried thereby, means for expanding and contracting said cutting tool and maintaining same at the desired diameter, and means for withdrawing the excavated material through said hollow shaft.

20. An apparatus of the character described, comprising a platform or scow surrounding three sides of an opening formed therein, the fourth side being free from obstructions, a hollow shaft adjustably mounted on said scow adapted to operate within the opening aforesaid and provided with an expandable cutting tool mounted on its lower end, means for raising, lowering and revolving said hollow shaft and the cutting tool carried thereby, means for expanding, contracting and securing the said expandable cutting tool to the size desired, means for withdrawing the excavated material through said hollow shaft, in combination with a hollow shell made in sections and adapted for lining the excavation made by said cutting tool, and means for holding and lowering said hollow shell.

21. An apparatus of the character described comprising a platform or scow having an opening or notch in one side thereof free from obstructions at its outer edge, means for anchoring said scow, a hollow shaft provided with an expandable cutting tool adapted to operate within the opening aforesaid, means for raising, lowering and

revolving said hollow shaft and the cutting tool carried thereby, means for contracting, expanding and securing said expandible cutting tool to the size desired, suction or 5 pumping devices connected with said hollow shaft for removing the excavated material therethrough, in combination with a hollow cylindrical shell made in sections, and means for holding and lowering the same to pro-

vide a lining or casing for the shaft of the 10 excavation formed by said cutting tool.

In testimony whereof I hereto affix my signature in the presence of two witnesses.

STEWART K. SMITH.

R. A. BEERS.

Correction in Letters Patent No. 987,266.

It is hereby certified that in Letters Patent No. 987,266, granted March 2 1911, upon the application of Stewart K. Smith, of Vintondale, Pennsylvania, for an improvement in "Foundation Apparatus," an error appears in the printed specification requiring correction as follows: Page 6, line 80, the word "edges" should read *edge*; and that the said Letters Patent should be read with this correction therein that the same may conform to the record of the case in the Patent Office.

Signed and sealed this 2d day of May, A. D., 1911.

[SEAL.]

C. C. BILLINGS,
Acting Commissioner of Patents.
